(57) **CLAIM**

The ornamental design for an inflatable bed, as shown and described.

DESCRIPTION

FIG. 1 is a front perspective view of an inflatable bed showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof;

FIG. 7 is a rear elevational view thereof;

FIG. 8 is a front perspective view of an inflatable bed of a second embodiment showing my new design;

FIG. 9 is a top plan view thereof;

FIG. 10 is a bottom plan view thereof;

FIG. 11 is a right side elevational view thereof;

FIG. 12 is a left side elevational view thereof;

FIG. 13 is a front elevational view thereof; and,

FIG. 14 is a rear elevational view thereof.

The broken lines shown in the drawings represent portions of the inflatable bed that form no part of the claimed design.

1 Claim, 14 Drawing Sheets
